(57) **CLAIM**

The ornamental design for an audio mixer, as shown and described.

DESCRIPTION

FIG. 1 is a front perspective view of the front, top and right side of an audio mixer showing my new design;

FIG. 2 is a rear perspective view of the rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

Broken lines are used to show portions of the audio mixer that are not being claimed, and thus form no part of the claimed invention.
